UNITED STATES PATENT OFFICE.

SIGMUND SCHLESINGER, OF NEW YORK, N. Y.

TALKING MACHINE.

1,417,111.

Specification of Letters Patent. Patented May 23, 1922.

Application filed June 12, 1919. Serial No. 303,560.

To all whom it may concern:

Be it known that I, SIGMUND SCHLESINGER, a citizen of the United States, and resident of New York city, borough of Manhattan, 5 in the county of New York and State of New York, have invented certain new and useful Improvements in Talking Machines, of which the following is a specification.

One object of my invention is to provide 10 means to wind the driving spring of a talking machine motor by the to-and-fro operation of a handle, whereby also the cover of the machine may be simultaneously raised and lowered with such spring winding; another 15 object is to cause the automatic movement of the sound arm from the mid-portion of the music record to one side thereof, as to a position beyond the starting point of the needle over the record, with one movement of said handle for winding the spring, and to return the arm to an approximate starting position of the needle on the record upon the return movement of said handle; another 20 object of my invention is to cause the automatic placing of the needle upon the music record when the plate or disk carrying the record begins to rotate; a further object being to automatically control the brake for the spring motor according to the 25 to-and-fro movement of said handle to automatically release the brake when the sound arm has been brought to the starting position.

Other features of my invention will be 30 more fully hereinafter set forth and then pointed out in the claims.

Reference is to be had to the accompanying drawings forming part hereof, wherein—

Figure 1 is a partly broken plan view of 40 a portion of a talking machine embodying my invention;

Fig. 2 is a detached view of a portion of Fig. 1;

Fig. 3 is a cross sectional view looking 45 from the front of the machine;

Fig. 4 is a side view partly broken and partly in section;

Fig. 5 is an enlarged detail section;

Fig. 6 is an enlarged detail of the needle 50 controlling device;

Fig. 7 is a sectional detail of the brake mechanism; and

Figs. 8 and 9 are enlarged details of part thereof.

Similar numerals indicate corresponding 55 parts in the several views.

The numeral 1 indicates a casing of a talking machine of any suitable construction having a cover 2 hinged thereto at 3 in any well known manner. 4 indicates the rotative disk or plate having felt-like material 5 to support the music record or disk 6 in any well known manner. At 7 is a plate carried upon shelf or top 8 of casing 1, which plate pivotally carries the sound arm 65 9 in any suitable manner. In the example illustrated the sound arm is jointed at 10 to the tubular sound conducting member 11, journaled upon plate 7, whereby the sound arm may have vertical and lateral movements, in a well known manner. Since the foregoing parts are generally of any well known type they need not be further described, and the details thereof may be varied while co-operative with my improvements hereinafter described. 75

A spring-motor of any desired construction, well known in the art, is indicated at 12 suspended below plate 8 in a usual manner and has a back check ratchet 13 secured 80 to the spring winding shaft 14, the ratchet being co-operative with stop dog 15 (Fig. 3) in a usual or desired manner. The power

spring of the motor may be secured to shaft 14 or may be of the well known slip-spring 85 or friction connection with said shaft, if desired, to resist over-winding. At 16 is indicated a brake-disk carried by shaft 17 and rotated by a suitable train of gearing 18 from the power spring of the motor, in a usual 90

or desired manner, a ball governor being indicated at 19 to control the rotation of said disk, as usual. A brake member 20 co-operative with disk 16 is supported and operated by a lever 21 pivoted at 22 in an ordinary 95 manner. A spring 21^a moves the brake member from the disk. The usual spindle 23, driven by said train of gearing rotates

plate or disk 4 to rotate music record 6 in the usual way. For the purpose of my invention any other suitable motor, gear train and brake may be provided co-operative with 100 my improvements hereinafter described.

I provide means to wind the spring of the

motor by a to-and-fro movement of a handle or crank arm 24 which simultaneously operates to raise and lower the cover 2. For such purpose handle 24 is secured upon a transverse shaft 25 journalled in the casing and provided with an internal rack segment 26 and an external rack segment 27. The rack 26 is in mesh with a gear 28 loose on shaft 14 and provided with one or more spring-acting dogs 29 co-operative with a ratchet 30 secured on shaft 14 for rotating said shaft to the right where the handle 24 is rotated to the right (Figs. 4 and 5). Rack 27 is in mesh with a gear 31 loose on shaft 14 and carrying one or more spring-acting dogs 32 co-operative with a ratchet 33 secured on shaft 14 and having its teeth extending reversely to the teeth of ratchet 28, whereby upon the reverse movement of handle 24 and rack 27 (to the left in Fig. 5) the spring of the motor will be additionally wound and at the same time the cover 2 will be closed. The arrangement is such that movement of racks 26 and 27 once forward and back will suffice to wind the spring of the motor enough to operate the music record to render any musical composition thereon. Shaft 25 is shown provided with a crank arm 34 pivotally connected with a link 35 pivoted to cover 2 at 36 and shown operative in a slot 37 in shaft 8 (Figs. 1 and 3). The arrangement is such that when handle 24 is rotated from the lower dotted position (Fig. 4) upwardly to the right to partly wind the motor spring the cover 2 will be raised by arm 34 and link 35, and when the handle is moved reversely to further wind the motor spring the cover will be lowered. The cover can be raised and lowered by direct operation of the hand to cause link 35 and arm 34 to rotate shaft 25 to cause simultaneous winding of the motor spring without requiring handle 24. The arm 34 and link 35 may be located outside of the casing instead of within it if preferred.

I provide means to swing the sound arm 9 from the position over the record 6, where the music stopped playing, when shaft 25 is first rotated to wind the motor spring with the raising of cover 2 and to move the sound arm reversely approximately to the starting position of the needle on the record when said shaft is rotated reversely. For such purposes I have illustrated the following means:—A vertically movable and rotative shaft 37 is journalled in bearings carried by the casing, a stop 38 on said shaft co-operating with bearing bracket 39 to limit descent of said shaft, (Fig. 5). Said shaft is shown located below the sound arm and provided with a laterally extending crank-arm 37^a shown having a sector-like laterally disposed head or plate 40 adapted to co-operate with a corresponding plate 41 carried by sound arm 9, shown on the under

side thereof, whereby when said shaft is raised and rotated in one direction the sound arm will be raised and correspondingly rotated to lift the needle *a* from the record 6 and swing the arm to one side thereof, and when said shaft is rotated reversely said arm will be moved back to place the needle over the record near its edge and said shaft will return and descend. A cam 42 is secured upon shaft 25 beneath the lower end of shaft 37 adapted, when shaft 25 is rotated to the right in Fig. 5, to engage and raise shaft 37 and when said shaft is rotated reversely cam 42 will lower shaft 37. Upon shaft 25 is secured a cam 43 adapted to engage a disk 44 secured on shaft 37, whereby when shaft 25 is rotated to the right in Fig. 5 the cam 42 will first raise shaft 37 to cause plate 40 to engage plate 41, to tilt sound arm 9 upwardly to raise needle *a* from record 6, and thereupon cam 43 will engage disk 44 to rotate shaft 37 whereby its crank-arm 37^a will swing sound arm 9 to carry the needle and the sound box *b* to one side of the record to permit its removal and the replacement of another record on plate 4. Upon the lower part of the sound box is pivotally carried a rockable member or segment 45 shown pivotally supported upon a tubular extension 46 from the sound box 95 through which the needle holding screw *c* operates (Fig. 6). The sound box *b* may be of any suitable or usual construction. The lower edge 45^a of member 45 is curved to rest upon and co-operate with plate 4 or 100 the felt thereon, said member 45 being of such length from its pivot as to rest upon said felt and temporarily retain the needle *a* raised from record 6. Member 45 has a pinion 47 in mesh with a rack 48 at the 105 lower end of an arm 49 pivotally supported at 50 upon the sound box. The upper projecting end 49^a of arm 49 has angularly related surfaces 49^b, 49^c, adapted to co-operate with a spring 51, secured at 52 upon the 110 sound box. When member 45 is in the position shown in Figs. 4 and 6 it will rest upon felt 5 retaining the needle above record 6, but when plate 4 commences to rotate with the record, member 45 will be rotated by 115 said plate and pinion 47 will operate rack 48 and arm 49 to cause spring 51 to snap upon surface 49^c to cause arm 49 and rack 48 to in turn operate member 45 sufficiently far to finally raise it from felt 5 above the plane 120 of record 6 so that needle *a* may descend thereon, (Fig. 5), for the production of music as usual. When the playing has ceased the sound arm and box *b* will be over the mid-portion of the record, as usual, and member 45 will be raised from the record, as 125 stated, and in order automatically to cause member 45 to assume the starting position (Figs. 4 and 6), I provide an inclined projection 53, shown supported by shelf 8, in 130

position to engage projection 49^a of arm 49 to tilt said arm to cause rack 48 to operate pinion 47 to restore member 45 from the music playing position of Fig. 5 to the starting position of Fig. 4. When the sound arm is next moved toward record 6 during the rotation of shaft 25 to the left in Fig. 5, the lower part of member 45 will engage the edge of record 6, but crank arm 37^a will 10 continue to rotate, the plate 40 then sliding under plate 41, and cams 42, 43 will release shaft 37 to permit it to descend when shaft 25 comes to rest.

To automatically control the brake devices for the record I provide the following means:—A curved rack 54 is carried by an arm 55 that is secured to the tubular member 11 and extends beneath plate 7 (Fig. 5), which rack is in mesh with 15 a pinion 56 whose shaft 56^a is secured to a ratchet wheel 57. Said shaft is journalled on an arm 58, shown comprising two spaced members, (Fig. 5), which arm is pivoted at 59 to a bracket 60 below 20 plate 7 and supported by the casing. The free ends of the members of arm 58 are rigidly connected by a spacer 58^a, (Fig. 7). A spring 61, shown carried by bracket 60 and bearing against arm 58, normally retains 25 pinion 56 in mesh with rack 54, and permits said arm to move laterally for unmeshing of said pinion and rack. (Fig. 2). A spring pressed pawl 62 is pivotally carried by a crank arm 63 pivotally supported at 30 64 upon a plate 65 shown also supporting bracket 60, (Fig. 1 and 2), which pawl co-operates with ratchet wheel 57 to rotate the latter and pinion 56. An eccentric 35 66 secured on shaft 23 is rotated with plate 4 and record 6 and actuates arm 63 to cause pawl 62 to operate ratchet 57 and pinion 56. A spring pressed back stop pawl 67 co-operates with ratchet 57 to resist its 40 reverse rotation. A lever 68 is pivotally supported at 69 and has a projecting end portion 68^a to engage the adjacent end of arm 58 to retain pinion 56 in mesh with rack 54, when brake member 20 is released from disk 16 (Fig. 1), said projection engaging 45 the opposite side of said end of arm 58 when the brake is applied, (Fig. 2). The lever 68 has a downward projection 68^b at the end opposite projection 68^a (which projection 68^b may pass through a hole in plate 8), the 50 projection 68^b being adapted to engage the lever 21 to shift member 20 to disk 16 when projection 68^a is over arm 20 (Fig. 2) to retain the brake applied. A spring 70 co-operates with lever 68 to move its projection 55 68^a toward arm 58. As the sound arm 9 traverses the record 6 during playing the rack 54 operates with pinion 56 and pawl 62 operates with ratchet 57. When the 60 needle enters the final usual circular groove 65 in the record near its centre the sound arm no longer traverses the record but the continued rotation of eccentric 66 with the record causes pawl 62 to continue to rotate ratchet 57 and pinion 56, whereupon the latter rotating and operating on the then stationary rack 54 rides on and out of the latter and causes arm 58 to be moved outwardly until it slips past the end of projection 68^a which passes over said arm, (Fig. 2), finally unmeshing pinion 56 from rack 54, whereupon spring 70 causes lever 68 to move lever 21 causing the latter to operate brake member 20 to engage disk 16 to apply the brake and stop the rotation of the record and other parts. When the brake is to be released for starting the operation of a record the lever 68 is tilted (from the position of Fig. 2 to the position of Fig. 1) to release arm 58 to permit its movement by spring 61 to cause re-engagement of pinion 56 with rack 54 and removal of member 20 from brake disk 16. For such purpose I provide a lever 71 pivotally supported at 72 and having a projection 71^a near one end to engage and tilt lever 68. The lever 71 has a depending extension 71^b, operative through a hole in plate 8, (Fig. 7), for operation by a cam or member 73 secured on shaft 25. Said cam is adapted to operate lever extension 71^b when moving in one direction but not in the reverse direction. Extension 71^b is shown provided at its lower end with a finger 74 pivotally connected thereto at 75 and having a stop shoulder 74^a normally held against a corresponding stop 71^c on extension 71^b by a spring 76 that connects said finger with said extension, (Figs. 7 and 8). Finger 74 is free to swing to the side opposite said stops. A spring 77 connecting lever 71 with shelf 8 (or other abutment) normally draws lever 71 against a stop 78 which may be on shelf 8 (Fig. 2). Cam 73 is of such shape and dimension that when shaft 25 is rotated in the direction of arrow α in Fig. 5 to wind the spring of the motor, the cam 73 will pass finger 74 on its right hand side and tilt it to the left in Fig. 9 without disturbing the brake set against the motor spring tension, and on the return stroke of said shaft and cam the latter will engage finger 74 on its left hand side (Fig. 9), and will pass beyond said finger with the effect of swinging lever 71 on its pivot 72 to cause its projection 71^a to operate lever 68 to release brake member 20 from disk 16 and to release arm 58, whereupon spring 61 will cause said arm to move to mesh pinion 56 with rack 54, and arm 58 will engage projection 68^a to retain lever 68 and spring 21^a will operate lever 21 to move brake member 20 from disk 16 to retain the brake released. It will be understood from what has been stated that each time shaft 25 is rotated a suitable distance to and fro the cover will

130

be raised, the motor spring will be wound, the sound arm will be released and moved outwardly from the record and return and released at starting position and the brake 5 will be released after having been automatically set at the termination of the rendering of a composition by the record and needle. My improvements simplify the use of talking machines since all that the 10 user has to do is to rotate shaft 25 in one direction for a partial revolution, remove and replace a record, and return said shaft to the normal position.

Since shaft 25 can be rotated forth and 15 back by the raising and lowering of the cover 2 it will be understood that such operation of said shaft and cover can be utilized for the described movements or adjustments of the sound arm without regard 20 to winding the spring of the motor. In other words, the means described for winding the motor spring may be dispensed with, and other features of my invention utilized with a motor arranged to have its spring 25 wound in a well known manner, or an electric motor may be used instead of a spring motor.

Having thus described my invention, what I claim and desire to secure by Letters Patent is:—

1. A talking machine comprising a casing, a sound arm pivotally supported upon the casing for vertical and lateral movements, a rock shaft journalled in the casing 35 and means co-operative between the shaft and sound arm for raising the arm and swinging it to one side when the shaft is operated in one direction and to swing the arm reversely and lower it when the shaft is operated in a reverse direction and means to manually rock the shaft in opposite directions.

2. A talking machine comprising a casing, a sound arm pivotally supported upon the 45 casing for vertical and lateral movements, a shaft journalled in the casing, another shaft slidingly and rotatively carried by the casing and having means co-operative with the sound arm, and means co-operative between said shafts to move the second named shaft longitudinally to raise the arm and to rotate said shaft and the sound arm laterally when the first named shaft is rotated in one direction and to operate the second 55 named shaft and sound arm reversely when the first named shaft rotates reversely.

3. A talking machine comprising a casing, a sound arm pivotally supported upon the casing for vertical and lateral movements, a 60 shaft journalled in the casing, another shaft slidably and rotatively carried by the casing, the last named shaft having a crank arm co-operative with the sound arm and having a disk, the first named shaft having 65 cams one of which is co-operative with the

second named shaft to raise and lower it, the other of which cams is co-operative with the said disk to rotate the second named shaft to swing the sound arm in one direction or another when the first named shaft is rotated in opposite directions. 70

4. A talking machine comprising a casing, a sound arm pivotally supported upon the casing for vertical and lateral movements, a shaft journalled in the casing, another shaft 75 slidably and rotatively carried by the casing, the last named shaft having a crank arm provided with a head, the sound arm having a plate co-operative with said head, said shaft also having a disk, the first named shaft having cams one of which is co-operative with the second named shaft to raise and lower it, the other of which cams is co-operative with said disk to rotate the second named shaft to swing the sound arm in one 80 direction or another when the first named shaft is rotated in opposite directions. 85

5. A talking machine comprising a casing, a motor carried thereby, a record supporting plate operative by the motor, a sound arm, means to raise the sound arm and swing it over the record, said arm having a sound box with means to support a needle, a member 90 movably carried by the sound arm and co-operative with said plate temporarily to retain the needle off the record, said plate being co-operative with the member to operate the latter and permit the needle to engage the record. 95

6. A talking machine comprising a casing, a motor carried thereby, a record supporting plate operative by the motor, a sound arm, means to raise the sound arm and swing it over the record, said arm having a sound box with means to support a needle, a member 100 movably carried by the sound arm and co-operative with said plate temporarily to retain the needle off the record, said plate being co-operative with the member to operate the latter and permit the needle to engage the record, means to retain said member 105 out of contact with the record when the needle operates upon the latter during playing, and means to restore said member to position for co-operation with the plate when the sound arm is moved to the outer portion 110 of the record. 115

7. A talking machine comprising a casing, a motor carried thereby, a record supporting plate operative by the motor, a sound arm, means to raise the sound arm and swing it over the record, said arm having a sound box with means to support a needle, a member 120 movably carried by the sound arm and co-operative with said plate temporarily to retain the needle off the record, said plate being co-operative with the member to operate the latter and permit the needle to engage the record, a pinion connected with said member, an arm pivotally supported by 125 130

the sound box having a rack co-operative with said pinion and means to retain said arm in set position with said member above the record when the needle is co-operative therewith.

8. A talking machine comprising a casing, a motor carried thereby, a record supporting plate operative by the motor, a sound arm, means to raise the sound arm and swing it over the record, said arm having a sound box with means to support a needle, a member movably carried by the sound arm and co-operative with said plate temporarily to retain the needle off the record, said plate being co-operative with the member to operate the latter and permit the needle to engage the record, a pinion connected with said member, an arm pivotally supported by the sound box, having a rack co-operative with said pinion, means to retain said arm in set position with said member above the record when the needle is co-operative therewith and means co-operative with said arm to cause it to restore said member in position to co-operate with said plate when the sound arm is moved to the outer portion of the record.

9. A talking machine comprising a casing, a motor carried thereby, a record supporting plate operative by the motor, a sound arm, means to raise the sound arm and swing it over the record, said arm having a sound box with means to support a needle, a member movably carried by the sound arm and co-operative with said plate temporarily to retain the needle off the record; said plate being co-operative with the member to operate the latter and permit the needle to engage the record, a pinion connected with said member, an arm pivotally supported by the sound box having a rack co-operative with said pinion and means to retain said arm in set position with said member above the record when the needle is co-operative therewith, said arm having a projection, and an inclined member carried by the casing located at one side of said plate in position to co-operate with said projection to cause said arm to restore said member in position to co-operate with said plate when the sound arm is moved to the outer portion of the record.

10. A talking machine comprising a casing, a record supporting plate, a motor to operate the plate, a sound arm, a rack operative with the sound arm, a pinion co-operative with the rack, a brake to control the motor, means co-operative between the pinion and brake, and means co-operative between the motor and pinion to operate the latter to cause setting of the brake.

11. A talking machine comprising a casing, a record supporting plate, a motor to operate the plate, a sound arm, a rack operative with the sound arm, a pinion co-operative

with the rack, a brake to control the motor, means co-operative between the pinion and brake, and means co-operative between the motor and pinion to cause the latter to ride on the rack for release therefrom to cause setting of the brake.

12. A talking machine comprising a casing, a record supporting plate, a motor to operate the plate, a sound arm, a rack operative with said arm, a pinion co-operative with the rack to cause relative movement of one to the other, a support movably carrying said pinion, means operative with the motor to rotate the pinion in co-operation with the rack when the latter and the sound arm are at rest after playing, a brake for the motor and means co-operative between said support and brake for setting the brake when the pinion and support move from the rack.

13. A talking machine comprising a casing, a record supporting plate, a motor to operate the plate, a sound arm, a rack operative with the arm, a pinion co-operative with the rack to cause relative movement of one to the other, a support movably carrying said pinion, means operative with the motor to rotate the pinion in co-operation with the rack when the latter and the sound arm are at rest after playing, a brake for the motor, means co-operative between said support and brake for setting the brake when the pinion and support move from the rack, a lever to actuate the last named means, and means to actuate said lever.

14. A talking machine comprising a casing, a record supporting plate, a motor to operate the plate, a sound arm, a rack operative with the arm, a pinion co-operative with the rack to cause relative movement of one to the other, a support movably carrying said pinion, means operative with the motor to rotate the pinion in co-operation with the rack when the latter and the sound arm are at rest after playing, a brake for the motor, means co-operative between said support and brake for setting the brake when the pinion and support move from the rack, a lever to actuate the last named means, means to raise the sound arm and move it outwardly across the record and to move the sound arm reversely for a distance in position over the record, and means operative by the last means to control the brake setting means to release the brake.

15. A talking machine comprising a casing, a record supporting plate, a motor to operate the plate, a sound arm, a rack operative with the arm, a pinion co-operative with the rack to cause relative movement of one to the other, a support movably carrying said pinion, means operative with the motor to rotate the pinion in co-operation with the rack when the latter and the sound arm are at rest after playing, a brake for the motor, an arm co-operative with the brake and with

- the pinion support to retain the pinion in mesh with the rack when the brake is released, said arm co-operating with said pinion support to set the brake when the pinion moves away from the rack and means to actuate said arm to release the brake and pinion to permit the latter to mesh with the rack.
16. A talking machine comprising a casting, a record supporting plate, a motor to operate the plate, a sound arm, a rack operative with the arm, a pinion co-operative with the rack to cause relative movement of one to the other, a support movably carrying said pinion, means operative with the motor to rotate the pinion in co-operation with the rack when the latter and the sound arm are at rest after playing, a brake for the motor, an arm co-operative with the brake and with the pinion support to retain the pinion in mesh with the rack when the brake is released, said arm co-operating with said pinion support to set the brake when the pinion moves away from the rack, means to actuate said arm to release the brake and pinion to permit the latter to mesh with the rack, a lever to actuate said arm, a cam to operate said lever, and a shaft carrying said cam.
17. A talking machine comprising a casting, a record supporting plate, a motor to operate the plate, a sound arm, a rack operative with the arm, a pinion co-operative with the rack to cause relative movement of one to the other, a support movably carrying said pinion, means operative with the motor to rotate the pinion in co-operation with the rack when the latter and the sound arm are at rest after playing, a brake for the motor, an arm co-operative with the brake and with the pinion support to retain the pinion in mesh with the rack when the brake is released, said arm co-operating with said pinion support to set the brake when the pinion moves away from the rack, means to actuate said arm to release the brake and pinion to permit the latter to mesh with the rack, a lever to actuate said arm, a cam to operate said lever, a shaft carrying said cam, said lever having a finger co-operative with said cam and movable in one direction by the cam independent of the lever and movable with the lever to actuate it when the cam moves reversely.
18. A talking machine comprising a casting, a motor to operate a record supporting plate, a sound arm pivotally supported to traverse the record on the plate, a rack operative with the arm, a pinion co-operative with the rack, an arm supporting the pinion for movement toward and from the rack, a ratchet connected with the pinion, a pawl co-operative with the ratchet, an arm carrying the pawl, an eccentric operative by the motor to actuate the last named arm, a brake for the motor, an arm to control the brake and co-operative with the first named arm to retain the brake released and set according to the position of the first named arm and pinion, and means to operate the third named arm to release the brake and permit remeshing of the pinion with the rack.
19. A talking machine comprising a casting, a motor to operate a record supporting plate, a sound arm pivotally supported to traverse the record on the plate and provided with a rack, a pinion co-operative with the rack, an arm supporting the pinion for movement toward and from the rack, a ratchet connected with the pinion, a pawl co-operative with the ratchet, an arm carrying the pawl, an eccentric operative by the motor to actuate the last named arm, a brake for the motor, an arm to control the brake and co-operative with the first named arm to retain the brake released and set according to the position of the first named arm, a pinion, and means to operate the third named arm to release the brake and permit remeshing of the pinion with the rack, a lever co-operative with the third named arm, a cam to actuate the lever, and means to operate the cam.

Signed at New York, in the county of New York and State of New York this 9th day of June, A. D. 1919.

SIGMUND SCHLESINGER.
